UNITED STATES PATENT OFFICE.

ALFRED ROPP, OF SAN FRANCISCO, CALIFORNIA.

ROASTING-FURNACE.

SPECIFICATION forming part of Letters Patent No. 532,013, dated January 1, 1895.

Application filed February 19, 1894. Serial No. 500,754. (No model.)

To all whom it may concern:

Be it known that I, ALFRED ROPP, a citizen of the United States, residing in the city and county of San Francisco, State of California, 5 have invented an Improvement in Roasting-Furnaces; and I hereby declare the following to be a full, clear, and exact description of the same.

My invention relates to an improvement in 10 furnaces for roasting ores.

It consists essentially in a novel means for stirring and advancing the ore through the furnace.

Referring to the accompanying drawings 15 for a more complete explanation of my invention,—Figure 1 is a transverse vertical section through $x-x$ of Fig. 2. Fig. 2 is a horizontal section through $w-w$ of Fig. 1. Fig. 3 is a transverse vertical section through $y-y$ 20 of Fig. 2. Fig. 4 is a transverse vertical section through $z-z$ of Fig. 2. Fig. 5 is a longitudinal vertical section on line 5—5 Fig. 4.

A represents the roasting chamber having a hearth B and an arched top C. The hearth B has a central longitudinal channel D made through it as shown. In the present case the hearth proper is supported upon suitable iron or other plates B' which are turned upwardly in the center leaving a narrow channel between them, the height being sufficient to prevent the ore from falling down through this channel.

Beneath the furnace is an open chamber E, within which a four-wheeled truck F is 35 adapted to travel one pair of wheels being exposed and the other shown by dotted lines in Fig. 2. From this truck an arm G extends upwardly through the channel or slot in the hearth, and across its upper end is a supporting bar H from which the rabbles or stirring teeth I project. This truck preferably runs upon tracks in the chamber beneath the furnace, and these tracks are continued exterior to the furnace at each end to pass around 40 in a curve so as to return parallel with the furnace and exterior to it.

J J are pulleys which serve to guide and also transmit power to a cable K which is attached to the car at opposite ends.

50 When the car is in motion, it is drawn along by the movement of the cable passing beneath the furnace, and by means of the up-

wardly projecting bar and the rakes carried by it, the ore is stirred and moved along through the furnace at any desired rate of speed. After leaving the furnace the car passes around upon the track exterior to the furnace and during its passage and return to the point of commencement it becomes sufficiently cool and ready to again enter the furnace.

Each time that the stirring apparatus enters the furnace, an automatic mechanism is put into action which delivers a suitable proportion of the raw material into the furnace from a hopper or receptacle above. This mechanism is shown in Figs. 2, 4 and 5 and comprises a shaft M belted to a driven shaft M' provided with a tappet m which engages a lug o on the lower side of a slide O' in the bottom of the hopper O.

The open ends of the furnace may be closed by flexible or swinging doors L of metal, asbestos, or other suitable material so that when the car reaches either of the doors 75 it will be displaced to allow the car to pass and again close after the passage of the car.

I prefer to fill the space in the chamber through which the car travels by a filling E', so as to leave only room for the car to pass 80 and thus reduce the amount of air which can enter through this chamber.

Having thus described my invention, what I claim as new, and desire to secure by Letters Patent, is—

1. A roasting furnace comprising a roasting chamber having a hearth, a central longitudinal truck or car chamber exterior to the roasting chamber, the said two chambers being connected by a narrow longitudinal slot, a car 90 or truck traveling in the car or truck chamber and having an arm projecting vertically through said slot into the roasting chamber, a rake or rabble in the roasting chamber and connected between its ends to said arm whereby it will rake the material on the hearth at 95 both sides of the said slot, substantially as herein described.

2. A roasting furnace comprising a roasting chamber provided with a hearth having a central longitudinal slot, dividing it through its length, a car or truck chamber beneath said hearth and communicating with the roasting chamber through said slot, a track extending

through the car or truck chamber and having a return branch exterior thereto, an endless cable corresponding with the track, a car or truck connected with the said cable to be drawn thereby around the track, and provided with an arm extending upwardly through the slot into the roasting chamber, and a rake secured between its ends to the upper end of the arm and crossing the slot to rake the material on the hearth at both sides of the slot, substantially as herein described.

3. In a roasting furnace, an inclosed chamber and hearth, fire-places and means for supplying heat to the chamber, a central longitudinal chamber situated beneath the furnace hearth, a channel extending from said chamber into the furnace and having upturned sides projecting above the surface of the hearth, a car traveling upon rails within the chamber and having arms projecting through the slotted channel, transverse arms

or stirrers connected with said arms, and an endless rope connecting with opposite ends of the car and following a continuation of the track exterior to the furnace whereby the car is alternately caused to traverse the length of the furnace and drag the stirrers through the material contained upon the hearth, and it is thence returned to the starting point exterior to the furnace, chambers situated beneath the hearth adapted to receive cars into which the ore is discharged after it has passed through the furnace, and doors at opposite ends which are opened automatically by the entrance and departure of the stirring devices and closed thereafter as herein described.

In witness whereof I have hereunto set my hand.

ALFRED RCPF.
